UNITED STATES PATENT OFFICE.

ERNST TÖPPER, OF KIEL, GERMANY.

LIFE-SAVING DEVICE.

1,070,430

Specification of Letters Patent. Patented Aug. 19, 1913.

Application filed November 22, 1912. Serial No. 732,976.

To all whom it may concern:

Be it known that I, ERNST TÖPPER, a subject of the German Emperor, residing at Kiel, Germany, have invented certain new and useful Improvements in Life-Saving Devices, of which the following is a specification, reference being had therein to the accompanying drawing.

This invention relates to life-saving devices and is designed especially for use in the case of sinking sub-marine boats.

The apparatus is secured inside of the sub-marine boat by a ball and socket joint, secured in such a manner that it may be operated entirely from within the boat. The apparatus is also adapted for use by "salvage" vessels, in which case it is secured to the sub-marine boat over one of its openings, so that it can be operated from either

20 the sub-marine or the salvage vessel. The apparatus consists in an accordion-shaped, folding casing, having metal rods and hinges fastened therein to plates and supports, being protected by an outer envelop or cover, consisting of rubber, air tight rubber coated linen, or the like, so that compressed air, which is to be pumped therein, will be retained and gradually force the device, to expand upwardly. Between 30 the hinges employed are provided supports or plates to maintain the structure in its longitudinal, or vertical position.

Two forms of the invention are shown in the drawing of which—
35 Figure 1, is a longitudinal section through the upper part of the device. Fig. 2 is a top plan view of the device, folded up. Fig. 3 is a cross section through a greatly inclined sub-marine boat, showing the life saving device partly pushed out. Fig. 4, shows the supports adjusted in three different positions. Fig. 5, is a bottom view of the life saving device. Fig. 6, is a vertical section fastened to the top, or over an opening, in the sub-marine. Fig. 7 is a cross section, taken on the line A—B, of Fig. 6, and Fig. 8, is a cross section showing the parts adjacent to the winch.

The device is composed of metal plates *e* equal in size, and fastened to quadrangular frames *e*² by means of hinges *e*¹, the longest edge of each plate *e* is again fastened by means of hinges to the next series, in such a manner that the parts will readily fold up, or cover the other like the sides of an ac-

Between the frames *e*², supports *t*, are secured which will stretch outwardly as the device is being pushed out, and will be held in position by the parts *t*¹, so they fall over 60 the joints of the supports *t*. At the lower part the device is provided with a door *d*. At the upper end the device has a receptacle *g*, which has at its lower part a door *c*, opening inwardly, while at its upper part it has 65 a door opening outwardly and still a further door *b*, opening inwardly.

When the device is not in use it is folded up as shown in Fig. 6, so that its upper surface is fastened to and will rest by its 70 flange on the detachable cover *l* of the device. At the lower part of the apparatus a winch *f*, is provided, arranged for four ropes an inlet *m* for compressed air will be found therein having an outlet in the chamber *g*. The four suspension ropes are of equal length and each rope is fastened to a drum of the windlass *f* and wound up as far as is necessary. The other end of the 75 ropes are passed through all the guide holes in the corners at the inner sides of the bail and they are then fastened to the lid *l* (see Fig. 1) or to the door *d*. (See Fig. 6.)

If the apparatus is to be used to save a sunken sub-marine it will be operated from the inside of the boat, as shown in Fig. 3, being constructed in a casing *A*, turnable in all directions.

When the device is to be used from a salvage vessel, it will be built in a cylindrical shaft *C* (see Fig. 6), having a removable cover *D*, having at its lower part two connecting curved tubes *i* and *k*, which are in connection with a valve *o*, by means of a door *d*.

The operation of the device in a sub-marine, is as follows: When the device is being pushed out, or being fastened on to the sub-marine, the latter, which may have sunk and be lying on one side will immediately be brought into a vertical position again. A man will then go from the boat through the door *d*, which will then be closed after him and the man will proceed on into the receptacle *g*. From the boat compressed air will now be forced through inlet *m* into the shaft whereby the receptacle *g* will be raised and after having reached its highest position will be secured by the projections *s*, on the cover *l*, to the receptacle *g*. The man in the receptacle *g* will signal to the parties in the boat, so that compressed air may be pumped

into the shaft and the parts gradually extended until the surface of the water has been reached. The man in the receiver equalizes the air through the valve *p*, opens the 5 hatches in the receiver *g* and gives notice to the persons in the boat, so that the latter can open the lower door *d*, and one after another, climb out of the boat through the shaft.

10 The manipulation of the apparatus from a "salvage" vessel, is as follows: The receiver *g*, (see Fig. 6) is drawn out of the casing *C* and with the lid *D*, is fixed by pins *s*. The pulling out of the receiver *g* (Fig. 6) is 15 effected while the apparatus is standing on the deck and a rope going from a crane or other lifting apparatus, not shown herein, is fastened to the inner side of the receptacle *g* and the same is pulled out so far with it, that the projectors can be projected. Then the apparatus is raised, and the curved tube *i* is turned to correspond to the position of the sunken sub-marine. One man then climbs into the receiver *g* and one man 20 into the receiver *k*, near the winch. Then the vents *a*, *b* and *d* of the apparatus are closed and there is let in through the valve *n*, into the curved tube *k*, as much compressed air as is required for the two persons in the apparatus, to breathe. The 25 vitated air goes off through the valve *p*. Then the apparatus is lifted off by an elevator and set up on the sunken sub-marine on one of the sky-lights where it is screwed fast by the divers. Then through the valve *n*, more compressed air is let in, which passes 30 through the open valve *o* into the curved tube *i*, and forces the water out of the same through the valve *r*. (The valve *r* has a hand wheel both inside and outside and can therefore be operated from both sides.) The man at the winch *f*, opens the door *d*, and closes the valve *r*, which can also be done by

the diver outside. Then the man goes back to the winch *f*. Then from the salvage vessel, or from the sunken sub-marine so much compressed air is let into the curved tube *k*, that the shaft *e* extends itself upward while the winch *f* is turned. Now when the receiver *g* has arrived at the surface of the 45 water, the man therein signals to the man at the winch *f*, to fasten the winch handle. Then the man in the receiver *g*, equalizes the air to the outside, through the valve *p*, and opens the vents in the receiver *g*. Then notice is given by the man at the winch or by the salvage vessel to the crew in the boat for them to open the vent *h*, and one after another to climb out of the boat, through the 50 apparatus.

Having now described the invention and the manner of using it, what I claim and desire to secure, is—

1. In a life saving apparatus an extensible waterproof casing having foldable, accordion-like sides, made of metal plates, hinges connecting said plates together, longitudinally adjustable supports in said casing means to inflate said casing and means to secure said casing to a boat.

2. In a life saving apparatus, a collapsible air tight shaft having a universal joint connection with a vessel, a door at the lower end of said shaft opening into said vessel, means to force air into said shaft, a receptacle at the upper end of said shaft and opening therewith, a top door and a side door in said receptacle, and means to operate the device.

In testimony whereof I affix my signature 80 in the presence of two witnesses.

ERNST TÖPPER.
